UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

FEELER-LOOM.

1,286,393

Specification of Letters Patent.

Patented Dec. 3, 1918.

Application filed December 26, 1916. Serial No. 138,833.

To all whom it may concern:

Be it known that I, JONAS NORTHRUP, a citizen of the United States, residing at Hopedale, in the county of Worcester and State of Massachusetts, have invented certain new and useful Improvements in Feeler-Looms; and I do hereby declare the following to be a full, clear, and exact description of the invention, such as will enable others skilled in the art to which it appertains to make and use the same.

The invention relates to an improvement in feeler looms, and more particularly to an improvement in thread parting mechanism for such looms.

A feeler loom is an automatic, weft replenishing loom in which the operation of the weft replenishing mechanism is controlled by a filling feeler mechanism which determines the amount of filling there is on the bobbin in the shuttle during the operation of the loom. When the filling has been unwound or exhausted to a predetermined extent, the filling feeler mechanism initiates the operation of the weft replenishing mechanism.

Feeler looms are commonly provided, at the side of the loom on which the weft replenishing mechanism is located, with thread parting mechanism, for severing the filling extending from the fell of the cloth to the shuttle, when the latter is boxed at that side of the loom on the replenishing beat-up of the lay, and for severing the filling extending from the hopper to the fell after the weft replenishing operation. The first-named filling end is known as the "outgoing" filling end, and the second-named filling end is known as the "incoming" filling end. One form of thread parting mechanism for severing the outgoing and incoming filling ends is disclosed in my copending application Serial No. 93,216, filed April 24, 1916. In this thread parting mechanism the parter blades are fastened at one end to a frame which is pivotally mounted, and are unsupported at their other or thread parting ends. These parter blades project through the reed dents continuously during operation of the loom. One object of the present invention is to improve the construction, organization and mode of operation of the thread parting mechanism disclosed in my said application, in order not only that the

thread parting operation may be performed more efficiently; but also that the wear on the thread parting members may be reduced.

A further object of the invention is to provide means of improved construction having provision for preventing the operation of the thread parting mechanism when, after a change of filling has been "called for" by the filling feeler mechanism, the weft replenishing mechanism is prevented from operating. As a result of preventing the operation of the thread parting mechanism when filling replenishment is called for but not consummated, the filling extending from the fell to the shuttle, while the shuttle is boxed at the weft replenishing side of the loom, will not be severed, and consequently there will be no filling end trailing from the shuttle to be caught in the shed when the shuttle is boxed at the side of the loom remote from the replenishing mechanism. Mispicks are thus prevented, and the time previously lost in removing these mispicks will be saved.

These objects and such others as shall hereinafter appear, are accomplished by the mechanism hereinafter described and particularly pointed out in the appended claims.

The preferred form of the invention is illustrated in the accompanying drawings, in which Figure 1 is a sectional elevation of the weft replenishing side of a loom, showing the application of the mechanism of the present invention thereto; Fig. 2 is a plan of the parts shown in Fig. 1; Figs. 3 and 4 are elevations similar to Fig. 1, certain parts of the loom and the thread parting mechanism being removed, and other parts being shown in different positions of operation; and Fig. 5 is a detail, on an enlarged scale, of one of the thread parting blades.

The mechanism of the present invention is particularly adapted for application to any usual or preferred type of feeler loom. In the loom illustrated in the drawings the weft replenishing mechanism, indicated by 100 the hopper plate 10, is located on one side of the loom, and the filling feeler mechanism, not shown in the drawings, is located at the opposite side of the loom and controls the operation of the weft replenishing mechanism through the usual rock shaft 11, which, in this instance, is hollow and extends transversely across the front of the loom,

being connected with the weft replenishing mechanism through a hopper arm 12, which is fixed on the rock shaft. The hopper plate 10 is supported by a bracket 13 fastened 5 on the breast beam 14. Secured to the upper end of the hopper arm 12 is an adjustable head 15 yieldingly held by a spring 16 against an arm 17 pivoted on a transerrer stud 18 in the hopper plate. A shuttle feeler 20 is pivoted on the hopper plate 10 at 21, and is connected with the transerrer arm 17 by a link 22. When the filling feeler mechanism detects critical or predetermined exhaustion of filling in the shuttle, the rock 15 shaft 11 is oscillated so as to cause the hopper arm 12 to swing to the right (viewing Fig. 1), and thereby initiate the operation of the weft replenishing mechanism. As the hopper arm 12 swings to the right, 20 the shuttle feeler 20 is swung into position to determine whether the shuttle 23 is properly boxed on the filling replenishing beat-up of the lay 25, which is the beat-up following the one on which critical 25 exhaustion of filling was determined. If the shuttle is not in proper position for the insertion of a fresh bobbin, it strikes the lower end of the shuttle feeler and pushes it forward toward the breast beam 14, thereby 30 preventing the completion of the weft replenishing operation. The operations of the parts just described are well known to those skilled in the art. The mechanism of the present invention is constructed so as to be controlled by these parts and to act in timed coöperation with them: first, to part the outgoing and incoming filling ends on succeeding beat-ups of the lay, and second, to prevent the parting operation if the weft replenishing mechanism is prevented from 35 completing the weft replenishing operation.

In addition to the parts above enumerated, the loom to which the mechanism of the present invention is applied is provided with a filling detector located on the same side of the loom with the weft replenishing mechanism. This filling detector is of usual construction and comprises a filling fork 27 pivoted at 28 on the rear end of a detector slide 29 mounted for sliding movements in a guideway or bracket 30 secured to the breast beam 14. When an intact filling is in front of the depending tines 32 of the filling fork 27, the fork is tilted, but when filling is not present in front of the fork on that beat-up, of the lay which corresponds to the forward movement of the weft hammer 33, the fork is not tilted, and consequently the hook 34 carried by the weft hammer 33 engages the fork 27 and, through it, pushes the slide 29 forward, thereby swinging the stop arm 35 to the right, viewing Fig. 1, so as to oscillate the stop shaft 37 to stop the loom.

The thread parting mechanism of the 65 present invention comprises a series of

loosely mounted, sheet metal parter blades 39. The forward ends of these parter blades are received in the interstices between a corresponding number of adjacent reed dents 40, and project through them continuously 70 during the operation of the loom. The reed dents are supported in the usual manner by the lay 25 and by the reed cap 41. The rear ends of the parter blades are provided with slots 38 so that they may be 75 loosely supported on one end of a rod 42, which is adjustably secured in a bracket 43 fastened to the loom frame. A guard 44, projecting downwardly from the inner end of the rod 42, is interposed between the 80 parter blades 39 and the warp threads 45 so as to prevent the latter from becoming entangled with the former. The forward ends of the parter blades are supported and normally held in raised position, as shown in 85 Fig. 1, by the rear end of a parter support 46. The slots 47 cut in the forward ends of the parter blades provide a loose connection between them and the rear end of the support 46. The purpose of supporting the 90 rear and forward ends of the parter blades in this manner is, that when the lay moves relatively to the blades on either its forward or return beats, a pulling strain rather than a pushing strain may be exerted on the 95 blades. In this way all tendency of the blades to buckle is eliminated. There is consequently but little friction between the blades and the reed dents. The wear on the latter, therefore, is negligible, and the 100 crystallization of the former is obviated.

The forward end of the parter support 46 is offset at right angles to its length, and is rigidly and adjustably secured in a hole in the upper end of an arm 49, in a hole in 105 the lower end of which is rigidly and adjustably secured one end of a rock shaft 50 journaled in a bearing 51 formed on a bracket 52 clamped to the bracket 13. The adjustability of the parter support 46 with 110 respect to the arm 49, and the adjustability of the rod 42 with respect to the bracket 43, provide for moving the parter blades 39 longitudinally relatively to the reed, so that when cloths of different widths are being 115 woven the parter blades may be positioned immediately outside the selvage so as to part the filling ends close to the selvage.

The forward ends of the parter blades are normally maintained in their raised position, 120 as shown in Fig. 1, by a cam controlled parter arm 54, which is rigidly and adjustably secured on the rock shaft 50 on the side of the bearing 51 opposite to that on which the arm 49 is located. It will be observed 125 that the parter support 46 and the parter arm 54 are in fixed relation, and practically constitute a bellerank lever. The rear end or cam boss 55 of the parter arm 54 projects downwardly and engages a parter con- 130

trolling cam piece 56 which rests on the base 57 of the hopper bracket 13. During normal weaving the cam boss 55 engages a high cam surface 58 on the cam piece 56, and 5 the rear end of the parter support 46, and consequently the forward ends of the parter blades 89, are held in a raised position. But, when the filling feeler mechanism has indicated predetermined exhaustion of filling 10 and the shuttle feeler is moved toward the lay into position to determine whether the shuttle has been properly positioned on the next weft replenishing beat-up of the lay, the cam piece 56 is moved to the rear 15 with it. For this purpose the rear end of the cam piece is provided with a slot 59 which is adapted to engage a pin 60 projecting laterally from a bracket 61 secured to and vertically adjustable on the shuttle 20 feeler 20. The movement of the cam piece 56 to the rear removes the cam surface 58 from under the cam boss 55 of the parter arm, and presents a recess or low cam surface 63 in the forward end of the cam piece 25 to the cam boss. Thereupon a spring 64 received in a housing 65 on the bracket 52, acts to push the cam boss 55 down into the recess 63 and thereby lower the forward ends of the parter blades toward the shuttle race 66, as shown in Figs. 3 and 4, into position to engage the outgoing filling and present it to the reed as the lay beats up on the filling replenishing beat.

During the weft replenishing operation 30 the shuttle feeler 20 remains in its rearmost position, as shown in Fig. 3. Upon the completion of the replenishing operation the lay beats back, and the shuttle feeler moves forward to the position shown in Fig. 4. As the shuttle feeler moves forward, the pin 60 carried thereby is moved into engagement with the forward end of the slot 59 and pushes the cam piece 56 forward until the rearmost end 68 of the recess 63 40 is brought under the rear end of the cam boss 55. This forward movement of the cam piece does not disturb the operative position of the parter blades, which still remain depressed toward the shuttle race, as 45 shown in Fig. 4, ready to engage the incoming filling end and present it to the severing action of the parter blades and reed dents as the lay beats up on the forward beat succeeding the replenishing operation. On this 50 beat-up of the lay, a bunter 69 fastened on the top of the shuttle box 70 engages the rear end of the cam piece 56 and pushes it forward into its normal position shown in Fig. 1. It will be observed in this connection 55 that while the shuttle feeler was in its operative position, as shown in Fig. 3, and the cam piece 56 was held in its rearmost position by the pin 60, the rear end of the cam piece was held above the path of motion of the bunter 69, which is shown by the

arrow; but, that when the shuttle feeler is in its inoperative position, as shown by Fig. 4, and the cam piece is in its secondary position, that is, half way between the position it assumes in Fig. 3 and the position it assumes in Fig. 1, the rear end thereof is in the path of motion of the bunter 69, as is shown by the arrow. It is thus seen that the cutting edges 67 of the parter blades are permitted to remain in operative position near the shuttle race during two successive forward beats of the lay, and that on the first of these, namely, the replenishing beat, the outgoing filling end is severed, and on the succeeding forward beat the incoming filling end is severed. Between these two beat-ups the parter blades are momentarily raised to permit the picking of the shuttle from the replenishing side of the loom, as will be presently explained.

The foregoing statement of the mode of operation of the thread parting mechanism presupposes a properly boxed shuttle on the replenishing beat-up of the lay. If on this beat-up of the lay the shuttle is not properly boxed, so that the shuttle feeler is moved forward and thereby operates to prevent the weft replenishing operation, the thread parting mechanism is also prevented from operating, and, consequently, the outgoing filling end will not be severed. In the present construction of loom, the non-operation of the replenishing mechanism when a change of filling has been called for by the filling feeler mechanism, does not result in loom stoppage. Consequently, if the outgoing filling end were severed on the beat-up of the lay on which the replenishing operation was scheduled to take place, the shuttle with its trailing filling end would be picked to the opposite side of the loom, with the consequent liability of a mispick resulting from the trailing filling end being caught in the shed. In order to obviate mispicks occurring from this cause, means are provided in the present invention to return the forward or thread parting ends of the parter blades to normal position if, on the replenishing beat-up of the lay, an improperly boxed shuttle strikes the shuttle feeler. The means for thus raising the forward ends of the parter blades comprise a cam piece 72 secured to the side of the parter arm 54. The cam piece 72 is provided with an opening 73, within which is situated during the normal operation of the loom a cam pin 74 projecting laterally from a boss formed on the forward side of the lower end of the shuttle feeler. As the shuttle feeler moves rearwardly into operative position, the cam pin 74 comes into engagement with a cam surface 75 formed on the rearwardly extending portion of the cam piece 72, and thereby momentarily raises the parter blades toward the upper part of the reed. When

the shuttle feeler has swung clear of the rearward end of the cam piece 72, the spring 64 acts as before described to depress the forward ends of the parter blades toward 5 the shuttle race. If, now, on the replenishing beat-up of the lay the shuttle is improperly boxed, and consequently it engages and pushes forward the shuttle feeler, the cam 74 will come into engagement with a 10 cam surface 76 formed on the rearward extremity of the cam piece 72. The relative positions of the cam pin 74 and cam surface 76 are such that the cam pin 74 is just passing under the lowest portion of the cam surface 76 as the reed dents 40 are passing by the cutting edges 67 of the parter blades. Consequently, inasmuch as the engagement of the cam pin 74 with the cam surface 76 acts to lift the forward ends of the parter 15 blades into inoperative position, the outgoing filling end is not caught between the cutting edges 67 and the reed dents 40, and so is not severed. When the forward ends of the parter blades have thus been raised 20 into inoperative position, to prevent the severing of the outgoing filling end, they are depressed again when the cam pin 74 passes beyond the cam surface 76. At this time the bunter 69 is under the rear end of 25 the cam piece 56. As the lay beats backward, the shuttle feeler follows it far enough to bring the cam pin 74 into engagement with the cam surface 75. The shuttle feeler moves rearwardly at this time because it is 30 under tension of the spring 16, the hopper arm 12 having not yet fully returned to normal position. The pin 74 engages the surface 75 to lift the parter blades immediately 35 previous to the picking of the shuttle from the replenishing side of the loom, so that the parter blades are above the path of the shuttle as the shuttle passes them. By the time the lay has completed its backward beat, the hopper arm 12, and consequently 40 the shuttle feeler, have been returned to normal position. The shuttle feeler and the parts connected with it are now in the positions shown in Fig. 4. On the following beat-up, the lay strikes and moves forward 45 the cam piece 56, thereby returning the parter blades to their normal or inoperative position. Inasmuch as the replenishing operation did not occur, there was no severing of filling on this beat-up of the lay. 50 From this description it will also be understood why the parter blades are temporarily raised after the replenishing operation to permit the shuttle to be picked, and are again returned to operative position 55 to sever the incoming filling end.

The mechanism of the present invention has been described as being applied to a feeler loom. It will be understood, however, that the invention is not restricted to application to feeler looms, but may be used in

connection with filling detector controlled, automatic looms. In this latter type of loom the rock shaft, controlling the weft replenishing mechanism, is actuated by the usual filling detector upon a detection of filling absence. Consequently, there can be no outgoing filling end. The thread parting mechanism of the present invention, nevertheless, if applied to this type of loom, would be thrown into operative position on the initiation of the replenishing operation, and would operate, as described, to sever the incoming filling end extending from the hopper to the fell of the cloth on the beat-up of the lay succeeding the replenishing opera- 80

The specific form of loom illustrated in the drawings is provided with a filling detector located on the weft replenishing side of the loom. It is obvious, however, that 85 the mechanism of the present invention is equally applicable to double filling detector looms, that is, to looms provided with a filling detector at each side, and to single filling detector looms where the filling detector, 90 is located on the one side of the loom or on the other.

The thread parting blades of the thread parting mechanism have been described as coöperating with the reed to sever the filling. 95 It will be understood that in place of the reed dents a grid or other similar toothed structure carried by the lay may coöperate with the thread parting blades to sever the filling. The invention, therefore, is not restricted to thread parting mechanisms in which the reed constitutes one of the thread parting members.

Having thus described the nature and scope of the present invention, what is 100 claimed is:

1. A loom having, in combination, weaving devices including a lay, parter members fixed on the lay, parter blades received between the parter members to coöperate with them to sever the filling, means for loosely supporting the blades at their rear ends from a stationary part of the loom, and means for loosely supporting the blades at their forward ends.

2. A loom having, in combination, a lay, weft replenishing mechanism, parter members fixed on the lay, parter blades received between the parter members to coöperate with them to sever the filling, means for supporting the blades at their rear ends, and means for supporting the blades at their forward ends, said latter means having provision for holding the blades above the filling during normal weaving and for lowering the blades to sever the filling on an actuation of the replenishing mechanism.

3. A loom having, in combination, weaving devices including a lay, parter members fixed on the lay, parter blades adapted to co-

operate with the parter members, and means for loosely supporting the blades at their rear and forward ends so that on each forward and backward beat of the lay the 5 parter blades may be moved a short distance in the direction of travel of the lay.

4. A loom having, in combination, a weft replenishing mechanism, a thread parting mechanism comprising parter blades adapted to project through the dents of a toothed member carried by the lay and coöperate therewith to sever the filling, a shuttle feeler, and means connected with the shuttle feeler for holding the thread parting ends 10 of the parter blades in inoperative position during normal weaving and for moving the thread parting ends of the blades into operative position when the shuttle feeler is moved into operative position.

5. A loom having, in combination, a weft replenishing mechanism, a lay, a toothed member thereon, parter blades adapted to coöperate with the toothed member to sever the filling, means for loosely holding the 15 parter blades suspended above the plane of the filling during normal weaving, means for lowering the thread parting ends of the blades below the plane of the filling when the weft replenishing operation is initiated, 20 and means for raising the thread parting ends of the blades above the plane of the filling if the weft replenishing operation is prevented.

6. A loom having, in combination, a weft replenishing mechanism, a shuttle feeler, a thread parting mechanism comprising parter members fixed on the lay and parter blades coöperating therewith, means connected with the shuttle feeler for holding 25 the parter blades in inoperative position during normal weaving and for moving the parter blades into operative position when the operation of the weft replenishing mechanism is initiated, and means controlled by 30 the shuttle feeler for moving the parter blades into inoperative position when on the replenishing beat-up of the lay an improperly boxed shuttle strikes the shuttle feeler.

7. A loom having, in combination, a lay, 35 weft replenishing mechanism, a shuttle feeler, parter members fixed on the lay, feeler, parter members for coöperation with the

parter members to sever the filling, means for supporting the rear ends of the blades, and connections between the forward ends 55 of the blades and the shuttle feeler, said connections having provision for holding the blades above the filling during normal weaving, for lowering the blades on initiation of the replenishing operation, and for 60 raising the blades in case the shuttle feeler is struck by an improperly boxed shuttle on the replenishing beat-up of the lay.

8. A loom having, in combination, a lay, weft replenishing mechanism, a shuttle feeler, 65 parter members fixed on the lay, parter blades coöoperating with them to sever the filling, means for supporting the rear ends of the blades from a stationary part of the loom, and connections between the 70 forward ends of the blades and the shuttle feeler for moving the blades into and out of filling severing position.

9. A loom having, in combination, a weft replenishing mechanism, a shuttle feeler, 75 a thread parting mechanism having parter blades, a cam piece loosely connected with the shuttle feeler, a bellcrank lever in engagement with the cam piece for holding the parter blades in inoperative position 80 while the shuttle feeler remains in inoperative position, and means for moving the parter blades into operative position when the shuttle feeler moves into operative position.

10. A loom having, in combination, a weft replenishing mechanism, a shuttle feeler, a thread parting mechanism having parter blades, a bellcrank lever connected with the 85 parter blades, connections between the shuttle feeler and the bellcrank lever adapted to maintain the parter blades in inoperative position during normal weaving and to permit the parter blades to move into operative position when the filling replenishing 90 operation is initiated, and means connected with the bellcrank lever constructed and arranged to be actuated by the shuttle feeler to move the parter blades into inoperative 95 position if the shuttle feeler is engaged by 100 the shuttle on the replenishing beat-up of the lay.

JONAS NORTHRUP.
